GILBERT E. RYDER, OF LEONIA, NEW JERSEY, ASSIGNOR TO THE SUPERHEATER COMPANY, OF NEW YORK, N. Y.

LOCOMOTIVE TENDER WITH OIL SEPARATOR.

Application filed October 10, 1925. Serial No. 61,867.

My invention relates to the construction of locomotive tender tanks and has specific reference to the provision of means which may be built into such tanks for the purpose of separating oil from contaminated water which it is desired to return to the tanks.

Where heaters of the closed type are used for heating the feed water of locomotives by means of exhaust steam, the amount of condensate formed in the heater is too large for direct discharge to the track or up the locomotive stack and for this reason, as well as because of the advantage to be derived from conserving the locomotive water supply, the condensate is returned to the locomotive tender tank.

The condensate as discharged from the heater is, however, unsuitable for direct return to the tender tank, as it is contaminated with lubricating oil and other impurities of a heavier nature carried over from the engine cylinders by the exhaust steam. It is necessary, therefore, to provide some means of separating this oil before the condensate is returned to the tank. The usual location of feed water heaters of this type is only slightly above the level of the top of the tender, with the condensate return being effected by gravity. Because of the low head available for the return of the condensate to the tender, it is necessary that the oil be removed by a filter or separator which imposes little if any resistance to the flow in the return line.

The object of the present invention is, therefore, the provision of a separator which may be cheaply and readily installed in existing tender tanks or applied to new tanks, and which will effectively remove the oil and other impurities from a condensate return line before discharging the condensate into the tank. It is a further object of the invention to provide a device of this character which will impose no resistance to flow in the condensate return line, and other and more detailed objects of the invention will become apparent as the following description proceeds.

In the accompanying drawing, I have shown in vertical section a preferred form of my invention as applied to a locomotive tender tank.

Referring to the figure, the tank is represented generally at 1, and has the usual bot-

tom sheet 2, top sheet 3, filling opening and cover plate 4, with the sheet 5 separating the water space of tank 1 from the coal space 6 of the tender. An opening 7 is provided in the bottom sheet 2, through which is inserted the casing 8, which extends from a point somewhat below the level of sheet 2 upwardly to the sheet 3, to which it is securely attached in any suitable manner, as by riveting or welding. The opening 7 in sheet 2 is closed by means of a depending sheet 9, forming a chamber 10 beneath the open end of the casing 8, the sheet 9 being secured to sheet 2 in any approved manner to form a water tight joint. As will be noted from the figure, the opening 7 is slightly larger than the casing 8 extending therethrough, so that an open passage from the chamber 10 into the main tank is provided through opening 7 outside the casing 8. The condensate return pipe 11 enters the top of the casing 8 through an opening in the sheet 3, and is preferably provided at its discharge end with a fitting 12 to direct the flow therefrom against the wall of the casing, although this latter feature is not essential to the operation of the device. An overflow pipe 13, having an inlet substantially level with the top of the tank is provided, this pipe most conveniently passing downwardly through the casing 8, and out through an opening in the sheet 9, although if desired, this overflow may be carried through the side of the casing and the tender tank, as it is essential only that the overflow have an inlet near the top of the tank and operate by gravity flow. The overflow pipe may be left open, or if desired a valve 14 for closing the pipe may be provided, in which case an atmospheric vent 15 is provided in sheet 3 to establish communication between the top of the casing 8 and the outside air. A valved drain 16 is provided for the removal of sludge accumulations from chamber 10.

The operation of the device is as follows: When the tender tank is filled, water flows into the casing 8 through the open lower end thereof until the level in the casing is the same as that in the main tank, the pipe 13 or vent 15 preventing the formation of an air pocket in the upper end of the casing as the water level therein rises. Condensate flows through the return pipe 11 into the casing, and tends to raise the water

level therein above that in the surrounding tank, but as the tank and casing are in open communication with each other, the water levels are equalized by flow from the casing 5 into the tank by way of the chamber 10 at the bottom of the casing. The downward flow of the water through the casing is very slow because of the large cross sectional area provided thereby and ample opportunity 10 is given for the light oil carried over in the condensate to separate and rise to the surface within the casing, while carbonized oil and the other heavier impurities carried by the condensate settle to the bottom of chamber 10 from which they may be from time to time removed through the valved drain 16. As the casing extends below the level of the bottom of the tank, the separated oil, indicated at 17, even though the main 15 tank is completely empty, is trapped and held within the casing 8. Tanks of this character are invariably, in normal operation, filled until they overflow, and the filling operation thus raises the water level in the tank, and also in the casing 8, to the 20 top thereof. When the tank is thus filled, the oil and other impurities floating on the surface of the water in the casing 8 are discharged through the overflow pipe 13, which forms a means for periodically removing the accumulation of impurities automatically whenever the tank is completely 25 filled.

It will thus be seen that I have provided 30 simple and inexpensive apparatus which will operate to effectively remove oil and other floating impurities from condensate returned to the tender, which creates no re-

sistance to flow in the condensate return line, and which is entirely automatic in 40 operation.

I claim:

1. In apparatus of the class described, the combination with a locomotive tender tank, of a casing extending downwardly therein, means forming a passage establishing communication between the lower portion of said casing and said tank with a portion of said passage lying wholly below the level of the bottom of said tank, a condensate return pipe opening into said casing, and an overflow pipe leading from the upper portion of said casing. 45

2. In apparatus of the class described, the combination with a locomotive tender having a chamber formed by a depression in the bottom of said tank, of a casing having an open end located in said tank with its open end extending into said chamber, a condensate return pipe opening into said casing, and an overflow pipe leading from the upper portion of said chamber. 50

3. In apparatus of the class described, the combination with a locomotive tender tank, having an opening in the bottom sheet thereof, of an open ended casing adapted to be inserted through said opening, said casing being attached at its upper end to the top sheet of said tank and extending at its lower end through said opening, a sheet closing 65 said opening, said sheet forming a chamber encompassing the lower end of said casing, a condensate return pipe discharging into said casing, and an overflow pipe leading from the upper portion of said casing. 70

GILBERT E. RYDER.
